UNITED STATES PATENT OFFICE.

LEE DE FOREST, OF NEW YORK, N. Y.

AUTOMATIC SWITCHING DEVICE FOR TELEPHONE SYSTEMS.

1,170,882.

Specification of Letters Patent.

Patented Feb. 8, 1916.

Application filed July 7, 1915. Serial No. 38,399.

To all whom it may concern:

Be it known that I, LEE DE FOREST, a citizen of the United States, residing in the city of New York, county of Bronx, and State of New York, have made a certain new and useful Invention in Automatic Switching Devices for Telephone Systems, of which the following is a specification.

This invention relates to automatic switching devices for telephone systems, and is especially designed for use in connection with radio telephone systems.

The object of the invention is to provide a relay device for automatically controlling the transmitter and receiving circuits.

A further object of the invention is to provide means which are automatic in action to connect the transmitting apparatus with the radiating antenna system when the voice is to be transmitted and to disconnect said connections and establish connection with the receiver when sounds are to be received.

Other objects of the invention will appear more fully hereinafter.

The invention consists substantially in the construction, combination, location and relative arrangement of parts all as will be more fully hereinafter set forth, as shown in the accompanying drawing and finally pointed out in the appended claims.

Referring to the accompanying drawing, Figure 1 is a view in diagram illustrating one form of arrangement of automatic switching device embodying my invention.

Fig. 2 is a similar view showing a modified arrangement included within the scope of my invention.

One of the defects of wireless telephone systems as practically operated is that it is impossible to carry on a continuous back and forth communication without switching the connections from transmitting to receiving condition, and back again so as to utilize the same antenna system both for receiving and transmitting, it being impossible to receive and transmit at the same time with the same antenna system. In practice it is customarily proposed to employ a manually operating switch to effect the proper shifting of the circuit connections. This materially impairs the efficiency and the speed of telephonic communication since an operator must throw the switch after talking into the transmitter so as to place the apparatus in

condition for receiving before he can receive a message transmitted to his station and

back again into transmitting condition before he can again transmit a message.

It is among the special purposes of my present invention to provide an automatic switch device which is voice controlled to the extent of effecting an automatic connection of the circuits into a transmitting condition by the sound waves of the voice when a message to be transmitted is spoken into the transmitter, the apparatus being normally in receiving condition and being restored to receiving condition at the cessation of the voice sounds.

In the accompanying drawing I have shown various arrangements for accomplishing these purposes. In Fig. 1 of the drawing N is the antenna of a radio system which in the transmitting part thereof includes the usual oscillator K, the terminals of which are connected to a suitable current source through the leads S. Associated with the oscillator K in the usual manner is a capacity P and inductance V. J, K' are terminals designed to be put into circuit connection with the antenna N, through a conductor arm 2. The terminal J is in circuit with the receiving or detector circuit through wire X in the usual manner. The terminal K' is in circuit through transformer coil T, wire 5, to the back contact L of a microphone. The front contact L' of which carries the diaphragm D in the usual manner, the carbon or other conducting granules or medium C being interposed between said contacts L, L'. The microphone diaphragm D is connected to earth at E. M is the mouthpiece of the microphone. When the contact lever 2 is in contact with terminal K', the antenna earth circuit may be traced from the antenna N through the tuning inductance W, lever 2, terminal K', coil T, wire 5, through the microphone to the earth at E. This is the arrangement for transmitting. When the conductor lever 2 is in contact with terminal J the antenna is connected to the receiving system. It will be observed that the transformer coil T is associated in the usual manner with the inductance V of the oscillating system.

In practice the conductor lever 2 is normally in contact with terminal J and in accordance with my invention I propose to provide automatic means operated by either the sound waves of the voice or by exhalation of the breath in speaking to disconnect the lever 2 from terminal J and to connect it

with terminal K'. When the apparatus is in normal condition, that is when the antenna is connected to the receiving system and the antenna earth circuit is opened at terminal K', it is also preferable to open the oscillating circuit. I therefore provide a terminal L² in the oscillating circuit with which coöperates a conductor member 3 which is associated with the lever 2 to move coincidentally therewith so that when lever 2 is in contact with terminal J, member 3 is out of contact with terminal L² and when lever 2 is in contact with terminal K' member 3 is in contact with terminal L². In the latter condition the oscillating circuit is closed and the antenna system is completed to earth as above explained which is the condition for transmission. Associated with the lever 2 and member 3 is a member Z constituting the armature of a slow relay S', a coil of which includes a battery B, a suitable and preferably adjustable contact G extending into the mouthpiece M of the microphone and with which coöperates a contact F on a loosely mounted member F' suspended within the mouthpiece M and transversely thereacross in position to be held toward the contact G by the action of sound waves impinging thereon or by the action of the breath exhaled by the operator when speaking into the mouthpiece.

The operation is as follows:—Assuming that the apparatus is in the condition shown in Fig. 1, *i. e.*, in condition for receiving communications, the one receiving the communication, in order to reply, without manually operating any switch, merely talks into the mouthpiece M of the microphone, the exhalation of the breath, or the force of the sound waves impinging on the diaphragm F', causing the contact member F thereof to make contact with the contact member G, thereby closing the circuit of and energizing the relay S' thereby attracting the armature Z, breaking contact with arm 2 and the lead X to the receiving apparatus, and completing the circuit of the antenna through the microphone, through arm 2, contact K', diaphragm D and earth E, and at the same time by means of arm 3 and contact L², providing the necessary oscillating current through leads S, inductively associated with the antenna earth system through the coils V, T. It will be seen that when speech ceases, contacts F and G separate thus opening the circuit of relay S' and allowing the switch arms 2 and 3 to again resume the position shown in Fig. 1, and putting the system in condition to receive communications as above described.

In Fig. 2 I have shown a similar arrangement wherein I employ a different means for automatically switching the antenna to the receiving and transmitting systems. In this form of my invention, I replace the

diaphragm and contact arrangement of F, F' and G in the mouthpiece M, by a capillary tube O opening into the mouthpiece M at U. This tube O is preferably U-shaped in length, the end Q thereof being sealed and forming one terminal of the circuit of the relay S'. Mercury, or any other conducting fluid R is located in the tube which also has a terminal at its lowest point to insure contact with the conducting fluid at all times, 75 said terminal Y being the remaining terminal of the circuit of the relay S'. The remaining elements of the device are the same as described hereinbefore. The operation is also identical except that the energizing of the relay S', is secured by the exhalations of the breath, or the sound waves or both, together with the capillary action of the tube O and conducting fluid R, completing the electrical connection between terminals Y and Q. 80

It will be understood that many other arrangements will occur to those skilled in the art for accomplishing the objects and purposes of my invention without departing from the broad scope thereof as defined in 90 the claims.

It will be readily seen that I have supplied an automatically operated switching device that is exceedingly simple in construction and which will allow a wireless telephone 95 station to be operated as both a receiving and a transmitting station, without manually operating switches, and which causes no delay in the change from receiving to transmitting arrangement, or vice versa, and 100 eliminating the possibility of having messages cross each other by having two stations transmitting at the same time, as such a condition would be readily detected.

Having now set forth the object and nature of my invention, and having described arrangements for carrying out the same, I claim:

1. In a radio telephone system, an antenna, receiving and transmitting circuits, 110 said antenna being normally connected to said receiving circuit and means controlled by the voice for automatically connecting said transmitting circuit to said antenna when said system is used for transmission. 115

2. In a radio telephone system, an antenna, receiving and transmitting circuits, and means controlled by the voice for automatically connecting said transmitting circuit to said antenna only when said antenna 120 is used for transmission.

3. In a radio telephone system, an antenna, receiving and transmitting circuits, voice controlled means for automatically connecting said transmitting circuit to said antenna and means for maintaining said connection only as long as transmissions are made. 125

4. In a radio telephone system, an antenna, receiving and transmitting circuits, 130

- voice controlled means for automatically connecting said transmitting circuit to said antenna and means for automatically breaking said connection when transmission ends.
5. In a radio telephone system, an antenna, receiving and transmitting circuits, and voice controlled means to connect said antenna to said transmitting circuit.
6. In a radio telephone system, an antenna, receiving and transmitting circuits, and means operated by the exhalation of the human breath in speaking for connecting said antenna to said receiving circuits.
7. In a radio telephone system, an antenna normally connected to a receiving circuit, a normally open transmitting circuit, and voice controlled means to automatically open said receiving circuit and close said transmitting circuit.
8. In a radio telephone system, an antenna normally connected to a receiving circuit, a normally open transmitting circuit, and means controlled by sound waves to automatically open said receiving circuit.
9. In a radio telephone system, an antenna normally connected to a receiving circuit, a normally open transmitting circuit, and means controlled by sound waves to automatically close said transmitting circuit.
10. In a radio telephone system, an antenna normally connected to a receiving circuit, a normally open transmitting circuit, and means controlled by the exhalation of the human breath in speaking for opening said receiving circuit.
11. In a radio telephone system, an antenna normally connected to a receiving circuit, a normally open transmitting circuit, and means controlled by the exhalation of the human breath in speaking for closing said transmitting circuit.
12. In a radio telephone system, an antenna normally connected to a receiving circuit, a normally open transmitting circuit, and means controlled by the exhalation of the human breath in speaking for opening said receiving circuit and closing said transmitting circuit.
13. In a radio telephone system, a receiving system, a transmitting system and a common antenna therefor, a switch for connecting said antenna to either of said systems, and automatically operated voice controlled means for actuating said switch.
14. In a radio telephone system, a receiving system, a transmitting system and a common antenna therefor, a switch for connecting said antenna to either of said systems, and voice controlled means for automatically operating said switch.
15. In a radio telephone system, a receiving system, a transmitting system and a common antenna therefor, a switch for connecting said antenna to either of said systems, and voice controlled means for operating said switch, said means being operated by the closing of a normally open circuit.
16. In a radio telephone system, a receiving system, a transmitting system and a common antenna therefor, a switch for connecting said antenna to either of said systems, and means for operating said switch, said means being controlled by a make and break circuit device and voice controlled means for operating said device.
17. In a radio telephone system, a receiving system, a transmitting system and a common antenna therefor, a switch for connecting said antenna to either of said systems, and means for operating said switch, said means being controlled by a make and break circuit device, operated by sound waves.
18. In a radio telephone system, a receiving system, a transmitting system and a common antenna therefor, a switch for connecting said antenna to either of said systems, and means for operating said switch, said means being controlled by a make and break circuit device operated by the exhalation of the human breath in speaking.

In testimony whereof I have hereunto set my hand on this 21st day of June, A. D. 1915.

LEE DE FOREST.
